RAILWAY MOTOR

Filed March 8, 1929

UNITED STATES PATENT OFFICE

DAVID T. WILLIAMS, OF NEW YORK, N. Y.

RAILWAY MOTOR

Application filed March 8, 1929. Serial No. 345,542.

The object of the invention is to provide an improved power structure for use in a locomotive, embodying an internal combustion engine, a compressor operated by said engine, and a compressed air driven motor for driving the driving wheels of a locomotive operated by the air from the compressor, whereby, as a primary feature, a conservation of space is effected, through the utilization of the exhaust products of the engine and motor, to first cool the compressed air by means of the exhaust products of the motor, to increase the amount of air that may be stored within the available space, and thereafter to raise the temperature of the compressed air by means of the exhaust products of the engine to a degree suitable for use in the motor cylinders, thereby, by the saving of the space by said cooling of the air, providing a power structure of dimensions within the limited confines of a locomotive, and achieving the saving in space by the employment of otherwise exhausted and wasted products.

In the use of compressed air motors for the purpose of propelling railway vehicles, much trouble has been experienced through the tendency of the exhaust passages to clog up with frost or ice derived from the moisture that is present in the atmosphere under practically all normal conditions. It has been found necessary to pre-heat the air before admission to the working cylinders to prevent this result, and even when this expedient is employed, it is found to be impossible to use high ratios of expansion, the great adiabatic drop resulting therefrom tending to cool even highly heated compressed air to below the freezing point.

It has also been found necessary to provide for a substantial storage capacity for the high-pressure compressed air, involving the paradoxical requirement of cooling the air from the compressor in order that an adequate amount may be stored, and re-heating the said air when drawn from storage for use in the motor cylinders in order to prevent freezing.

This invention is directed to a means whereby the otherwise waste heat may be

utilized to effect the above thermal changes without employing independent heaters, as has heretofore been deemed necessary.

The improvement claimed is hereinafter fully set forth.

The accompanying drawing is a diagrammatic delineation of a power plant comprising a Diesel engine, an air compressor directly connected thereto, and the associated members illustrating an approved embodiment of the invention.

Referring descriptively to the approved embodiment thereof which is herein exemplified by the drawing, a water-cooled internal combustion engine 1, is directly connected to a water-cooled air compressor 2. A receiver 3, containing cooling means, is provided for the storage of air compressed by the compressor, and intermediate receivers 4 and 5, provided with heating means, are interposed between the receiver 3 and a multi-stage air motor, to which they are connected by suitable conduits hereinafter more particularly described. The receiver 3 is in the form of a conventional heat exchanger comprising a cylindrical shell 3c, a tube sheet 3d at each end of the shell, tubes 3e secured in the tube sheets, and a header 3f at each end of the shell. Compressed air is led from the compressor 2, through the pipe 2a, into the shell 3c, and partially expanded compressed air for cooling the stored air is led by the pipe 8d into the header at one end of the receiver and passing through the tubes 3e, enters the header at the other end of the receiver, from which header it escapes to the atmosphere by a pipe 3b. The intermediate receivers 4 and 5 are similar in construction to the receiver, 3.

A multi-stage air motor, comprising a high pressure stage cylinder 6, and two low pressure cylinders 7a, 7b, receives the treated air from the intermediate receivers 4 and 5, and is operatively connected to driving wheels 14 of the locomotive. Connected to each of the pistons of cylinders 7a and 7b is a piston rod 13 which drives a connecting rod 13a connected to a crank pin on a driving wheel 14. Connected to the piston of the cylinder 6 is a piston rod 15, which drives a connecting

rod 15a connected at one end to the crank 15b of the wheel axle 15c. The aforesaid cylinders are provided with jackets exteriorly encompassing their walls, exhaust gases from the water-cooled internal combustion engine 1 being caused to flow through said jackets for the purpose of heating said walls.

Water is circulated through jackets surrounding the cylinders of the internal combustion engine 1, and the cylinders of the air compressor 2, and thence led to a receptacle 8 containing cooling means through which the air exhausted from the multi-stage motor cylinders 7a, 7b is passed to cool the circulating water. The receptacle 8 is in the form of the usual heat exchanger and is similar in its structural details to the receiver 3.

The above members are provided with ducts as follows: a duct 9, having branches 9a conveys cooled circulating water to the jackets of the internal combustion engine 1, and the air compressor 2; a duct 10, having branches 10a returns the heated circulating water to the receptacle 8, wherein it is cooled and again passed through said jackets; and a duct 11 conveys the products of combustion exhausted from the engine 1. Two branches 11b and 11f extend from the duct 11 and the branch 11b is provided with branches 11d, 11e, 11c to convey exhaust gas to the jackets of the multi-stage air motor cylinders 6, 7a and 7b. The branch 11f conveys exhaust gas to the heating means associated with the intermediate receiver 5, from whence said exhaust gas is conveyed to the heating means associated with the receiver 4 by means of a duct 11g, and after passing through said means, said exhaust gas is discharged to the atmosphere through the ducts 11h and 3b.

A duct 2a conveys the compressed air from the compressor 2 to the receiver 3; a duct 3a, fitted with a valve 3a' conveys compressed air from the receiver 3 to the intermediate receiver 4; a duct 4a, having a pressure controlling valve 4b, of usual form, embodying the well known principles of the Foster, Mason or Leslie pressure control valves, affords communication for compressed air from the intermediate receiver 4 to the receiver 5; and a duct 4c conveys compressed air from the intermediate receiver 4 to the distribution valve 6a of usual construction, associated with the high pressure or first expansion stage air motor cylinder 6.

A duct 5a conveys partially expanded air exhausted from the cylinder 6 to the intermediate receiver 5, and a duct 5b conveys compressed air received from receiver 4 and the partially expanded air from intermediate receiver 5 to distributing valves 7 of usual construction, associated with the second expansion stage cylinders 7a, 7b, through the branches 5d, 5c.

65 A duct 8a, having branches 8b, 8c conveys

the finally expanded air exhausted from the final expansion stage cylinders 7b, 7a, to the cooling means associated with the receptacle 8; a duct 8d, conveys said air from said cooling means to the cooling means associated with the receiver 3; and the duct 3b conveys said air from said cooling means of receiver 3, to the atmosphere.

70 My invention seeks as one of its objects to accomplish the cooling of the circulating water by using, as a cooling agent, air expanded in the multi-stage motor to the lowest practicable temperature, to wit, just above freezing.

75 Also in the instant invention the air stored in the receiver 3 is cooled by the air that has first been used to cool the circulating water in the receptacle 8.

80 Air thus cooled, if expanded through an appropriate temperature range in the first stage, or high-pressure cylinder 6 of the multi-stage air motor, would suffer such an adiabatic drop in temperature that any moisture contained in said air would speedily freeze and cause such an accumulation of 85 ice or frost as to disable the engine. Air is therefore drawn from the receiver 3 through the duct 3a, having the valve 3a', to the intermediate receiver 4, containing a heating means, such as a nest of tubes through 90 which the hot exhaust gases from the Diesel engine are circulated, thus heating and increasing the volume of the air before admission to the cylinder 6.

95 When the air is expanded in the cylinder 6, especially if the ratio of expansion therein be comparatively great, it will suffer a severe fall in temperature incident to the adiabatic expansion, and more heat must be imparted to such partially expanded air to prevent a 100 fall in temperature below the freezing point at the end of the subsequent stage of expansion in the cylinders 7a, 7b. Therefore, the invention contemplates subjecting the partially expanded air to the heating effect 105 of the exhaust gases from the Diesel engine before said gases are used to heat the air admitted to the first expansion stage, by admitting said gases to the heating means contained within the intermediate receiver 110 5, which receives exhaust air from the first stage cylinder 6, said heating means being preferably of the kind described as enclosed in the receiver 4, and then conveying the air thus re-heated together with any additional air supplied through the duct 4a to the cylinders 7a, 7b, of the final expansion stage.

115 Adiabatic cooling of the air in the multi-stage air motor is to a certain extent compensated for by heating exteriorly the walls of said motor. This is accomplished by circulating through the jackets thereof a portion 120 of the exhaust gases from the engine 1, the gases being exhausted to the atmosphere 125 130

- through the exhaust pipes 12. As is obvious to those skilled in the operation of locomotives, the ratio of expansion in the air motor cylinders will be varied from time to time as 5 the demands for power change. Hence different fractions of the whole amount of the exhaust gases may be required respectively by the jackets of the air motor cylinders and the heating means associated with the intermediate receivers 4 and 5, and, if desired, any 10 suitable well known means such as valves, (not shown) may of course be provided to control the flow of exhaust gases to the motor cylinder jacket and receivers 4 and 5.
- 15 It is apparent that if very short cut-offs entailing high ratios of expansion are used in the first expansion stage cylinder 6, the pressure of the receiver 5, would drop to very low values.
- 20 For many reasons, this is undesirable, and hence there is provided the reducing valve 4b, located in the conduit 4a, whereby under the above described conditions, air will be drawn from the receiver 4 in such amounts 25 as may be needed to supply the receiver 5 with sufficient air irrespective of the amount of air received from the cylinder 6.
- The invention claimed and desired to be secured by Letters Patent, is:
- 30 1. The combination of an air motor; an air storage receptacle; means for supplying air under pressure to the receptacle including an internal combustion engine; means for cooling the air in the receptacle to permit 35 the storage of an increased quantity of air within said receptacle; means for transmitting air from the receptacle to the air motor; means for heating the air during its transmission from the receptacle to the motor; and 40 means whereby the cooling and heating mediums are supplied from the respective exhausts of the air motor and internal combustion engine.
2. The combination of a multi-stage air 45 motor; an air storage receptacle; means for supplying air under pressure to the receptacle including an internal combustion engine; means for cooling the air in the receptacle to permit the storage of an increased quantity 50 of air within said receptacle; means for transmitting air from the receptacle to the first stage of the air motor for operating the same; means for transmitting air exhausted from said first stage of the air motor to a 55 second stage of said motor for operating the same; means for supplying exhaust from the second stage of the motor as the cooling medium to the means for cooling air in said receptacle; means for supplying exhaust 60 from the internal combustion engine to said air transmission means between said receptacle and said first stage of the air motor to heat said air prior to its introduction into said first stage; and means for supplying 65 exhaust from the internal combustion engine to the transmission means between the exhaust of the first stage of the motor and the second stage of the motor for heating the air exhausted from said first stage before its introduction into said second stage. 70
3. The combination of an air motor; an air storage receptacle; means for supplying air under pressure to the receptacle including an internal combustion engine; means for cooling the air in the receptacle to permit 75 the storage of an increased quantity of air within said receptacle; means for transmitting air from the receptacle to the air motor; means for heating air during its transmission from the receptacle to the motor; means for heating the air motor; means whereby exhaust air from the air motor will be supplied, as the cooling medium, to the means for cooling the air in the receptacle; and means 80 whereby the exhaust from the internal combustion engine will be supplied, as the heating medium, to the means for heating the air motor and will be supplied, as the heating medium, to the means for heating the air during its transmission from the receptacle to 85 the motor.
4. The combination of an air motor; an air storage receptacle; means for supplying air under pressure to the receptacle including an internal combustion engine; means for cooling the air in the receptacle to permit 90 the storage of an increased quantity of air within said receptacle; means for transmitting air from the receptacle to the air motor; means for heating air during its transmission from the receptacle to the motor; means for cooling the internal combustion engine; means whereby the exhaust air from the air motor will be utilized for cooling a cooling medium 95 to the means for cooling the internal combustion engine and will be subsequently utilized as the cooling medium to the means for cooling the air in the receptacle; and means for supplying the exhaust from the internal combustion engine, as the heating medium, to the means for heating the air during its transmission from the receptacle to the air motor. 100
5. For use in a locomotive, a high pressure air motor; a low pressure air motor; an air reservoir for power air for the high pressure air motor, communicating therewith; another air reservoir for power air for the low pressure motor, communicating therewith; a compressor for supplying air for said reservoirs; means for conveying exhaust air from the high pressure motor to the second mentioned reservoir whereby the air supplies for said second mentioned reservoir are commingled therein; means for supplying a heating medium to said second mentioned reservoir in heat exchange relation with the air contained therein; and means for conveying said heating medium from said second mentioned reservoir to said first mentioned reservoir. 110
- 115
- 120
- 125
- 130

voir for heating the air therein by heat exchange relation therewith.

6. For use in a locomotive, a high pressure air motor; a low pressure air motor; an air reservoir for power air for the high pressure air motor, communicating therewith; a compressor for supplying air for said reservoir; another air reservoir for power air for the low pressure motor, communicating therewith; means connecting the two reservoirs whereby the second mentioned reservoir is supplied with air from the first mentioned reservoir; means for conveying exhaust air

from the high pressure motor to the second mentioned reservoir, whereby said air supplies for said second mentioned reservoir are commingled therein; means for supplying a heating medium to said second mentioned reservoir in heat exchange relation with the air contained therein; and means for conveying said heating medium from said second mentioned reservoir to said first mentioned reservoir for heating the air therein by heat exchange relation therewith. 70 75
